(*) Notice: This patent is subject to a terminal disclaimer.

(57) CLAIM

(**) Term: **15 Years**

The ornamental design for a vehicle display screen or portion thereof with an animated graphical user interface, as shown and described.

(21) Appl. No.: **29/649,400**

DESCRIPTION

(22) Filed: **May 30, 2018**

FIG. 1 is a front view of a first image in a sequence for a first embodiment of a vehicle display screen or portion thereof with an animated graphical user interface;

(51) LOC (12) Cl. 14-04

FIG. 2 is a front view of a second image thereof;

(52) U.S. Cl.

FIG. 3 is a front view of a third image thereof;

USPC **D14/486**

FIG. 4 is a front view of a first image in a sequence for a second embodiment of a vehicle display screen or portion thereof with an animated graphical user interface;

(58) Field of Classification Search

FIG. 5 is a front view of a second image thereof; and,

USPC D14/485-495
CPC .. G06F 3/0482; G06F 3/04883; G06F 3/0481;
G06F 3/04842; G06F 3/0488; G06F
3/04817; G06F 3/04847; G06F 3/0485;
G06F 3/04886; G06F 3/0484; G06F
9/451; G06F 3/04845; G06F 3/0486;
G07F 17/32; G07F 17/3244

FIG. 6 is a front view of a third image thereof.
The appearance of the animated graphical user interface sequentially transitions between the images shown in FIGS. 1-3, and in FIGS. 4-6.

See application file for complete search history.

The process or period in which an image transitions to another forms no part of the claimed design.

(56) **References Cited**

The broken lines showing a display screen or portion thereof, forms no part of the claimed design.
